UNITED STATES PATENT OFFICE.

GEORGE GARRECHT, OF ST. LOUIS, MISSOURI, ASSIGNOR TO HAYNES-LANGENBERG MANUFACTURING COMPANY, OF ST. LOUIS, MISSOURI, A CORPORATION OF MISSOURI.

FURNACE.

1,087,875.

Specification of Letters Patent. Patented Feb. 17, 1914.

Application filed April 14, 1913. Serial No. 780,958.

To all whom it may concern:

Be it known that I, GEORGE GARRECHT, a citizen of the United States, residing at the city of St. Louis and State of Missouri, have invented a new and useful Furnace, of which the following is a specification.

This invention relates to furnaces and particularly to apparatus to be used in connection with furnaces popularly known as hot air furnaces for humidifying the air before it is introduced into the distributing system.

An object of the invention is to produce an apparatus of the type mentioned which will be automatic in action and which will supply to the air heating chamber of the furnace a constant and steady supply of vapor or steam, which mixes with the air and is carried with it throughout the distributing system.

With this general object, and incidental features which will be obvious from the following disclosure, in view, I have designed and arranged the several coöperating parts hereinafter more fully described, reference being made to the accompanying drawing in which—

Figure 1 is an elevation with a part of the different elements broken away, fully illustrating the several parts in their preferred arrangement constituting the present invention. Fig. 2 is a cross-section through the fire chamber of the furnace illustrating in detail the arrangement of the water heating unit.

In the embodiment of my invention illustrated in the drawing A indicates the furnace casing in which is located the drum or fire chamber B. Within the drum or combustion chamber B is located the fire pot formed with side walls of fire brick in the manner understood, and is adapted to contain a bed of coal or other suitable fuel. It will be understood, of course, that the heat from the fire pot radiates from the drum and heats the air which is introduced within the casing from any suitable source, and that the air thus heated is conducted from the casing through the air supply pipes C. In the embodiment shown, I have preferred to employ a canopy top D which is in the form of an inverted cone and assists in distributing the heated air, and in mixing therewith the vapor, in the manner hereafter more fully disclosed.

For producing the vapor which is to be mixed with the heated air I provide a tank 1 which is located exteriorly of the casing and is arranged to contain water, which circulates through a hollow chamber or water back 2 by means of the inlet and return pipes 3 and 4. The hollow chamber or water back 2 is arranged in the wall of the fire pot, as clearly shown in Fig. 2. The hollow chamber or water back 2 is preferably made the same size and shape, with respect to its outer dimensions, as a single fire brick employed in constructing the wall of the fire pot, thus facilitating the construction of the apparatus. Thus the water contained within the tank 1 is heated and gives off aqueous vapor which rises from the tank and passes into the casing A through the pipe 5, which communicates with said tank 1 above the water line. The pipe 5 is provided at its inner end with an upturned outlet passage 6, through which the vapor from the tank 1 is emitted into the casing A, preferably below the apex of the canopy D. The vapor is thus distributed throughout the heated air just as it enters the hot air distributing pipes C, forming a uniform mixture of air and moisture thereby producing humidified air of the proper relative moisture, for distribution through the system.

In order to maintain a constant supply of water within the tank 1, I provide a separate supply tank 7 which is connected by the pipe 8 with the tank 1 and may be provided with a drain valve 9, for draining tanks 1 and 7 when the apparatus is not in use. The tank 7 is kept constantly supplied with water through the supply pipe 10 connected with any permanent source of water supply, which pipe is controlled by a float valve of known construction indicated by 11, so that a predetermined level of water may be constantly maintained within the tank 7 thereby preventing the level of the water in the tank 1 from falling below a requisite level.

From the foregoing description, the operation of the apparatus is evident and it will be apparent that it is simple and durable in construction and positive and automatic in its operation, supplying the requisite amount of moisture for producing the required humidity of the air which is distributed through the heating system.

While I have described a preferred embodiment of my invention I do not desire to limit myself to the exact details shown and described, but what I claim and desire

5 to secure by Letters Patent is:

1. In combination with a furnace comprising a casing, air distributing pipes located near the upper part of said casing, a heating drum and a fire pot, of a tank located exteriorly of said casing, a water back constituting a part of the wall of said fire pot, an inlet and a return pipe between said tank and said water back, a steam conduit communicating with said tank above the
- 10 level of the water contained therein and extending into the upper end of said casing, a supply tank, a passage between said supply tank and said first-named tank, and a water service pipe automatically controlled by the level of water in said supply tank for supplying water to said tank, substantially as specified.
- 15 2. In combination with a furnace comprising a casing, air distributing pipes located near the upper part of said casing, a heating drum and a fire pot, of a tank located exteriorly of said casing, a water back constituting a part of the wall of said fire pot, an inlet and a return pipe between said
- 20 tank and said water back, a steam conduit located above the line of liquid contained in said tank and leading from said tank and

having open communication with the interior of said casing, a supply tank, a passage between said supply tank and said first- 35 named tank, a service pipe extending within and opening into said supply tank, a valve in said service pipe within said tank, and a float lever actuated by the water within said supply tank for controlling said valve, substantially as specified. 40

3. In combination with a furnace comprising a casing, air distributing pipes located near the upper part of said casing, a heating drum and a fire pot, of a tank 45 adapted to contain a liquid and located exteriorly of said casing, a water back arranged to be effected by the heat generated in said fire pot, an inlet and a return pipe between said tank and said water back, a 50 pipe constituting a conduit adapted to conduct vapor from said tank into said casing, a supply tank, a passage between said supply tank and said first-named tank, a water service pipe and automatic means for controlling said water service pipe, substantially as specified.

In witness whereof, I have signed this specification in the presence of two subscribing witnesses.

GEORGE GARRECHT.
